ARMAND BAILLY, OF PARIS, FRANCE.

PNEUMATIC HAMMER.

1,391,162.

Specification of Letters Patent. Patented Sept. 20, 1921.

Application filed July 7, 1920. Serial No. 394,591.

(GRANTED UNDER THE PROVISIONS OF THE ACT OF MARCH 3, 1921, 41 STAT. L., 1313.)

To all whom it may concern:

Be it known that I, ARMAND BAILLY, citizen of the Republic of France, resident of Paris, France, (post-office address, 46 Quai 5. Henri IV,) have invented a new and useful Pneumatic Hammer, (for which I have filed application in France Apr. 19, 1919, Patent 495,774,) which improvements are fully set forth in the following specification.

10 This invention relates to a pneumatic hammer characterized by a distribution which enables a hammer to be economically worked by compressed air, further to a movable ring construction which, during accidental withdrawal of the tool, avoids the imparting of any injurious shocks to the piston at the end of its travel; the whole being completed by a stop-cap for the tool, which stop-cap is easily detachable.

20 An embodiment of the invention is illustrated by way of example in the accompanying drawing.

Figure 1 shows in elevation and in longitudinal section the general arrangement of the hammer with the piston at the end of the left hand stroke.

Fig. 2 is a view of the cylinder cover with the exhaust pipe.

Fig. 3 is a partial section of the cylinder, 30 showing the piston at the end of the right hand stroke.

Fig. 4 is a side view of the front part of the cylinder.

Fig. 5 shows the same part in front elevation.

Fig. 6 is an end view of the stop-cap.

Fig. 7 is a sectional view of the stop-cap.

Fig. 8 is an end view of the safety ring, and

40 Fig. 9 is a sectional view of the safety ring, with a part of the cylinder and the piston.

The apparatus comprises as usual in apparatus of this kind, a handle *a* screwed on one end of a cylinder *b* in which travels the striking piston *c* which strikes the tool *e*; said handle thus embodying a portion which forms a cover or closure for said cylinder end, as will be understood from Figs. 1 and 2.

With the right hand part of the piston engages partially a tube *k* intended for the escape of the air which has done its work.

The compressed air is admitted through

the opening *f* of the cylinder; this admission is regulated by hand by means of a cock of any of the usual types.

The air admitted through opening *f* into the chamber *g* acts on the annular shoulder on the piston and pushes the latter to the right; when the piston uncovers the opening provided at *h* in the wall of the cylinder, the compressed air can pass to the other side of the piston and act on its right face *l* which stops the movement of the piston (Fig. 3), then starts it to the left.

In this movement toward the left, the part *d* of the piston first closes the port *h*, which stops the admission of compressed air to the right hand face of the piston; the piston, under the action of expansion of the air, continues to travel until its face *l* uncovers the end *m* of the exhaust tube *k*, as shown in Fig. 1.

The air escapes therefore through the central opening *n* of the tube *k* and then through the radiating holes *o* which are formed in the cover portion of the handle and open at their outer ends into an annular space *q* in the handle, the holes *o* intersecting at their inner ends in a common point. The space *q* encircles the aforesaid cover portion, and from it extend the outlet openings *q* for discharging the air into the atmosphere. Other shapes of conduits could be used for leading the exhaust air into the atmosphere.

After the exhaust, the piston strikes the tool *e*, stops and rebounds, and the air continuing to pass through opening *f* to its annular shoulder, causes it to begin again the same cycle, and so on.

The characteristic feature of this distribution is the use of the central tube *k* which makes it possible to regulate the moment of opening of the exhaust where it may be considered necessary, in order to obtain sufficient admission and sufficient expansion of the air which are generally obtained only by the use of a comparatively delicate part such as a slide or other valve, whereas the exhaust tube used here, is a fixed and strong part.

At the left hand end of the cylinder is the tool *e* on which the piston strikes. This tool is set in a ring *s* provided with special openings, the function of which is as follows:

In normal working, the air contained in the chamber *r* between the piston and the

tool, escapes from the cylinder and freely re-enters it at each reciprocation of the piston through the conduits *t* and the holes *u* provided in the ring *s*, and then through the 5 groove *v* and the holes *w* provided in the end of the cylinder *b*.

The holes *w* open under the envelop formed by the cylindrical part of the stop cap *A* so as not to be exposed direct to the 10 dust of the atmosphere.

As soon as the tool *e* ceases for any reason to be pressed toward the right, it moves to the left under the action of the piston and carries with it the ring *s*, which results in 15 covering the outlet holes *u* and the groove *v*, as shown clearly in Fig. 9; at this moment the air contained in the chamber *r* can no longer escape, and hence it is compressed and stops the piston before the latter strikes 20 the cylinder at the end of its stroke. This result is strengthened by the closing of the passage *f* for the admission of air to the cylinder; in fact, the movement to the left of the tool and of the ring enables the part 25 *d* of the piston to cover again the port *f* for the admission of compressed air, and the compression of the air contained in the closed space *g* contributes to stopping the piston as the latter moves toward the left 30 (see Fig. 9).

The stoppage toward the right is produced, in its turn, by the compression of the air in the closed space contained between the face *l* of the piston and the part *i* when the 35 part *d* of the piston covers and passes beyond the port *j*.

The stop-cap *A* which prevents the tool from coming out, must be easily detachable while offering no risk of becoming detached 40 from the cylinder during the working.

This object is attained by the system shown in detail in Figs. 3-7. The end of the cylinder has a series of equidistant thickened portions *D*, each provided with a recess *E*. 45 Between the said thickened portions *D* are left free passages *C*; through the said passages *C* can pass tenons *B* arranged in the interior of the cap *A* to the number corresponding to that of the passages *C*.

50 During the movement of introduction by hand of the cap *A* on the cylinder *b*, the spring *F* is compressed; thereupon, the cap *A* being sufficiently engaged to bring the tenons *B* into the free space *G*, the cap *A* 55 is turned about the cylinder *b*, so as to place the tenons *B* opposite the recesses *E*, then the cap *A* is released and brought by the thrust of the spring *F* into the working position shown in Fig. 1.

60 Reverse movements enable the cap *A* to be easily removed. During the working of

the hammer, the spring *F* keeps the tenons *D* in engagement with the recesses *E*. The number of the tenons and of the recesses is made greater or less at will. 65

The system of safety ring and stop cap described need not necessarily form an inseparable part of the hammer described. They could be separated from it and fitted together or separately to other constructions 70 of pneumatic hammer in which their use may be considered advisable.

I claim as my invention:

1. In a hammer, the combination of a cylinder; a handle connected to one end of the 75 cylinder and provided with a central discharge tube for the spent motive fluid and with ducts leading from said tube to the atmosphere, said tube extending into the interior of the cylinder; a reciprocating percussive piston in said cylinder having an inwardly-extending recess in its rear end to receive said tube; means for supplying motive fluid under pressure across the cylinder; an annular shoulder on the rear portion of the 80 piston to be acted on by said fluid; and a duct in the wall of the cylinder for bypassing the fluid from one side of said shoulder to the other. 85

2. In a hammer, the combination of a cylinder; a handle connected to one end of the cylinder and embodying a cover for said cylinder end formed internally with a plurality of radiating outlet holes which intersect at their inner ends at a common point 95 and open at their outer ends through the peripheral edge of the cover, said handle being formed with an annular space encircling said cover edge and with outlet openings leading from said annular space to the atmosphere; a central discharge tube for the spent motive fluid connected to said cover at its inner end and opening into said outlet holes at their point of intersection; a reciprocating percussive piston in said cylinder 100 having an inwardly-extending recess in its rear end to receive the outer end of said tube; means for supplying motive fluid under pressure across the cylinder; an annular shoulder on the rear portion of the piston 105 to be acted on by said fluid; and a duct in the wall of the cylinder for bypassing the fluid from one side of said shoulder to the other. 110

In testimony whereof I have signed this 115 specification in the presence of two subscribing witnesses.

ARMAND BAILLY.
